(57) **CLAIM**

The ornamental design for an automobile headlamp as shown and described.

DESCRIPTION

FIG. 1 is a top, front, right perspective view of an automobile headlamp, in accordance with an embodiment;

FIG. 2 is a bottom, front, right perspective view of the automobile headlamp of FIG. 1;

FIG. 3 is a bottom, front, left perspective view of the automobile headlamp of FIG. 1;

FIG. 4 is a bottom, front, left perspective view of the automobile headlamp of FIG. 1;

FIG. 5 is a front view of the automobile headlamp of FIG. 1;

FIG. 6 is a right view of the automobile headlamp of FIG. 1;

FIG. 7 is a left view of the automobile headlamp of FIG. 1;

FIG. 8 is a top side view of the automobile headlamp of FIG. 1; and,

FIG. 9 is a bottom side view of the automobile headlamp of FIG. 1.

The ornamental design which is claimed is shown in solid lines in the drawings. The broken lines of equal length dashes in the drawings are for illustrative purposes, depict environmental subject matter, and form no part of the claimed design. Broken lines formed by unequal length dashes (i.e., dash-dot) define bounds of the claimed design.
